UNITED STATES PATENT OFFICE.

GEORGE H. SYLVESTER AND ANDREW C. SYLVESTER, OF CARY STATION, ILLINOIS.

SHOVEL.

Application filed October 6, 1922. Serial No. 592,765.

To all whom it may concern:

Be it known that we, GEORGE H. SYLVESTER and ANDREW C. SYLVESTER, citizens of the United States, residing at Cary Station, in the county of McHenry, State of Illinois, have invented a new and useful Shovel, of which the following is a specification.

This invention relates to scoop shovels, and more particularly to scoop shovels especially designed for dredging lake or river beds.

The primary object of the invention is to provide a shovel of this character wherein the power employed for moving the shovel through the surface being dredged, may be utilized for dumping the shovel, eliminating the necessity of stopping the machine or power device to accomplish the dumping result.

Another object of the invention is to provide means for regulating the depth at which the shovel may work, adapting the shovel for various uses.

A still further object of the invention is to provide means for preventing the shovel from dragging material with it, while the same is being returned to its active or scooping position, by floating back when operating in water.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a side elevational view of the scoop in its active or scooping position.

Figure 2 is a sectional view through the scoop and disclosing the same in a dumping position.

Figure 3 is a top plan view of the scoop.

Figure 4 is a fragmental detail view disclosing in perspective, one of the cable supporting irons.

Referring to the drawings in detail, the shovel includes a frame comprising end sections 5, which end sections are connected by means of the bar 6 disposed at the upper ends thereof, the lower portions of the sections being connected by means of the bot-

tom plates 7, end plates 8 and rear plates 9 forming the body of the shovel.

Arms 10 are secured to the end plates 8 and extend forwardly therefrom, the arms providing supports for the rod 11 that supports the adjustable blade 12.

The ends of the blade 12 are bent upwardly as at 13 where they have connection with the arms 14 that in turn are pivotally connected with the bars 15, as at 16. These bars 15 extend to points adjacent to the bar 6, where the same are provided with openings to accommodate the right angled ends 17 of the rod 18, so that movement of the rod will result in a relative movement of the bars and blade associated therewith. Secured to one of the right angled ends 17 is a keeper 19 adapted to accommodate a portion of the lever 20 which is pivotally supported adjacent to the keeper. Thus it will be seen that by moving the lever 20 to a position as shown by Figure 1 of the drawings, movement of the lever will produce a relative movement of the bars 15 and rod 18, to the end that the blade supported at the forward end of the shovel may be adjusted at the will of the operator.

The cable supporting frame embodies side bars 21 that are connected by means of the bars 22 disposed intermediate the ends of the side bars 21 to hold the side bars in proper spaced relation with each other.

Brackets 23 are secured to the forward edges of the bars 21 adjacent to the upper ends thereof, so that they may hook over the bar 6 in a manner to support the cable supporting frame.

At the upper end of each of the bars 21 are the guides 24 arranged in spaced relation to accommodate the cables 25, the lower ends of the cables 25 being secured to the links 26 that are secured adjacent to the lower rear edge of the shovel adjacent to the ends thereof.

Associated with the guides 24 are pivoted latch members 27 formed with notched portions 28 to accommodate the cables 25, one end of each of the latch members extending beyond the bar 21 associated therewith to be engaged by the pivoted keeper 29 associated therewith, which keepers 29 are moved to their active and inactive positions by means of the operating rods 30 that in turn are controlled by the levers 31, that are pivotally connected to the bars 21.

At the upper ends of the cables 25 are keepers 32 which are formed with openings to accommodate the bolts 33 that extend through openings in the bars 34 so that the bars 34 may be adjusted with respect to their keepers to lengthen or shorten the dumping cables 35 that are connected to the poles 36. Thus it will be seen that due to this construction, one of the cables 35 may be shortened to cause the shovel to dig at a greater depth, at one side thereof.

The cables 35 also connect with the link 37, which link also has connection with the power cables 38 that extend over the ends of the pole 36 and carry links 39 at their free ends. Hook members 40 are pivotally connected to the rod 11, each hook member including a pivoted section 41 formed with an extension 42 adapted to cooperate with the 20 sliding latch member 43 to hold the pivoted section 41 associated therewith, in its active position. When the latch member 43 is moved from engagement with the extension 42, it is obvious that any pull directed to the 25 hook members 40 will swing the sections 41 to their inactive positions to release the cables 38 and direct the pull of the power device to the cables 35, causing the shovel to be tilted to its dumping position, as clearly 30 shown by Figure 2 of the drawings.

Hingedly connected to the forward portion of the shovel, is a door 49 adapted to move to a position to partially close the forward end of the shovel and prevent the 35 shovel from dragging material with it, while the same is being returned to a scooping position.

It is obvious that as the shovel is being drawn through the ground surface, the material passing into the shovel will cause the door 49 to move to a position in proximity 40 to the bottom 7 of the shovel.

Cables 50 have connection with the body portion at the rear thereof, which cables 45 operate over suitable pulleys not shown, to move the shovel to its initial or scooping position.

What is claimed as new is:-

1. In a scoop shovel, a body portion, a 50 pivoted blade supported adjacent to the forward edge of the body portion, pivoted hook members having connection with the body portion, power cables having connection with the hook members to draw the 55 shovel through the ground surface, cables extending over the body portion, means for supporting the cables above the body portion, means for releasing the power cables to direct the pull to the last mentioned 60 cables to cause the body portion to dump the contents thereof.

2. A scoop shovel comprising a body portion, a pivoted blade supported adjacent to the forward end of the body portion, power 65 cables having connection with the body por-

tion adjacent to the blade, dumping cables associated with the power cables and extending to the rear of the body portion, means for releasing the power cables to direct the pull to the dumping cables to dump the contents of the body portion.

3. A scoop shovel comprising a body portion, an adjustable blade pivotally supported at the forward end of the body portion to adjust the depth of operation of the 75 shovel, power cables releasably connected with the body portion, cables associated with the power cables and extending to points above the body portion and having connection with the body portion at the 80 rear thereof, means for releasing the power cables to direct the pull to the last mentioned cables to cause the body portion to dump, and a return cable for moving the body portion to its initial position.

4. A scoop shovel comprising a body portion, power cables having connection with the forward portion of the body, a cable supporting frame carrying brackets adapted to lie over the upper edge of the body 90 portion, cables associated with the power cables, means for connecting the last mentioned cables to the cable supporting frame, means for releasing the power cables to direct the pull to the last mentioned cables, 95 and said last mentioned cables adapted to direct the pull to the cable supporting frame to move the body portion to a dumping position.

5. A scoop shovel comprising a body portion, a pivotal blade disposed adjacent to the forward edge of the body portion, arms extending upwardly from the ends of the blade, bars having pivotal connection with the arms and extending to a point adjacent to the rear upper edge of the body, a lever for controlling the movements of the bars to adjust the blade and cause the body portion to operate at various depths, power cables for moving the body portion to the ground surface, cables associated with the power cables and disposed above the body portion, and means for releasing the power cables to direct the pull to the last mentioned cables for dumping the shovels.

6. A scoop shovel including a body portion, power cables releasably connected to the body portion, cables associated with the power cables and disposed adjacent to the upper side edges of the body portion, means for releasing the power cables to direct the pull to the second mentioned cables, and means for adjusting the lengths of the second mentioned cables to cause the shovel to operate at angles.

7. A scoop shovel including a body portion, power cables having connection with the forward portion of the shovel, dumping cables extending over the body portion, a cable supporting frame having connection 130

with the body portion at the rear thereof, means for releasably connecting the dumping cables to the cable supporting frame, means for releasing the power cables to direct the pull to the dumping cables to cause the dumping cables to move the shovel to a dumping position.

8. A scoop shovel including a body portion, power cables having connection with the body portion adjacent to the forward lower edge thereof, dumping cables associated with the power cables and extending over the body portion, means for releasing the power cables to direct the pull to the dumping cables causing the body portion to dump its contents, a rod supported adjacent to the upper portion of the body and having right angled ends, a keeper secured to one of the right angled ends, a pivoted blade at the forward end of the shovel, bars connecting the blade and rod, a lever having connection with the rod and adapted to be

positioned in the keeper to cause the bars to move and adjust the blade, when the lever is operated.

9. In a scoop shovel, a body portion, a power cable for moving the body portion to the ground surface, a dumping cable associated with the power cable for tilting the body portion, means for directing the shovel through the ground surface, and a pivoted door supported adjacent to the forward end of the body portion to close the forward end thereof when the shovel is being moved to its active position by floating.

In testimony that we claim the foregoing as our own, we have hereto affixed our signatures in the presence of two witnesses.

GEORGE H. SYLVESTER.
ANDREW C. SYLVESTER.
